[57] CLAIM

The ornamental design for an electric iron, as shown and described.

DESCRIPTION

FIG. 1 is a top and front and side perspective view of an

electric iron showing my new design;

FIG. 2 is a right side elevational view thereof;

FIG. 3 is a rear elevational view thereof;

FIG. 4 is a front elevational view thereof;

FIG. 5 is a top plan view thereof; and

FIG. 6 is a bottom plan view thereof.

The cord is shown broken away and the plug omitted in
FIGS. 2-6 for clarity of illustration.
